UNITED STATES PATENT OFFICE.

ADRIAN LIVINGSTON BOGART, OF NEW YORK, N. Y., ASSIGNOR TO
WILLIAM B. M. JORDAN, OF SAME PLACE.

IGNITING DEVICE FOR GAS-BURNERS.

SPECIFICATION forming part of Letters Patent No. 623,871, dated April 25, 1899.

Application filed May 5, 1897. Serial No. 635,176. (No model.)

To all whom it may concern:

Be it known that I, ADRIAN LIVINGSTON BOGART, a citizen of the United States, residing at New York, (Jamaica,) in the county of 5 Queens and State of New York, have invented a certain new and useful Improvement in Igniting Devices for Gas-Burners, of which the following is a specification.

My invention relates to an improved means 10 for utilizing the common torch in gas-lighting, and is more particularly useful in the ignition of what are known as "cluster-lights" (gas-jets grouped closely together around a central standard) where the same have chimneys of the incandescent or Argand type, or 15 to gas-burners surrounded by closed globes, as in pendent lanterns.

In the ignition of Argand or Welsbach incandescent gas-burners, as the lighted end of 20 the torch must be held over the tops of the chimneys the latter are liable to be broken, smoked, or displaced from their proper positions, and, further, it is a matter of extreme 25 difficulty to light all of the jets of a cluster without a change of position of the operator. Where a closed globe surrounds the cluster, much greater, if not entirely insurmountable, difficulty is presented.

The object of my invention therefore is to 30 avoid and entirely overcome the objections above stated and to produce by simple and inexpensive means a device by the use of which the ordinary gas-igniting torch may be employed to light gas-burners of the kind de- 35 scribed with ease and certainty without altering to any considerable extent the construction of such fixtures as have closed globes and without risk of breaking, displacing, or smok- 40 ing the chimneys and without requiring the operator to change his position.

My invention consists principally in the construction of a flash-pilot or ladder in such manner that the same shall project a jet of gas away from or below the cluster, fixture, 45 or globe, which is first ignited by the torch, such jet then serving to ignite the flash-pilot, which later performs the work of lighting the burners of the cluster. By this method in- 50 stead of the torch being put into position by the operator to reach the gas to be ignited it

is held away from the fixture at such a distance that it can neither smoke nor damage the latter or its parts, and the gas is automatically projected to the ignited end of the torch.

In the accompanying drawings, Figure 1 55 represents an embodiment of my invention as applied to a cluster of incandescent gas-lights in a pendent lantern with closed glass globe, the main controlling stop-cock being independent of the igniting-valve. Fig. 2 is an 60 open cluster, the main and igniting valves being operated simultaneously. Fig. 3 is a sectional view of the spring igniting-valve used in Figs. 1 and 2, but shown on a larger scale. Fig. 4 represents an open cluster with a spring- 65 cock instead of valve controlling the igniting device, the flash-pilot entering the base of the burners instead of terminating over the tops of the chimneys; and Fig. 5 is a side elevation of Fig. 4 with the burners removed to show 70 the relative positions of the igniting parts more clearly.

Referring to Fig. 2, I have shown an ordinary two-light cluster provided with a main stem A, a controlling stop-cock B, and two 75 branch arms provided with incandescent gas-burners C. Screwed into the bottom or body of the cluster is a valve D. Proceeding therefrom is a pipe E, pierced with holes and constituting a flash-pilot or ladder. Fig. 3 is an 80 enlarged sectional view of this valve, in which e is the gas-inlet pipe, which is screwed directly into the bottom of the fixture.

f is a conical valve which slides within the casing g, but is pressed firmly upward against 85 the valve-seat by means of a spiral spring h, thereby normally preventing the issuance of gas from the fixture to the valve-chamber. The lower prolongation of the valve f is a rod i, which passes through an opening, not 90 necessarily gas-tight, in the bottom of the valve-chamber g. From one side of the valve-chamber issues the flash-pilot tube E, which is provided with two openings in its wall, one above at j and the other below at k. If a 95 downward pull be exerted upon the stem i, as by means of the chain F, the plug f will leave its seat, permitting the gas to pass in through the passage e, and so out of and through the flash-pilot pipe E. The move- 100

ment downward of the valve-plug *f* is limited by the lower head of the valve-chamber *l*, the bottom of the plug *f* closing and making gas-tight the space, if any, about the stem *i*. The 5 main gas-cock *B* is provided with two arms *G G'*, to which chains or cords *II II'* are attached. These chains terminate in rings *I I'*. The lever *G'* in the drawings represents that one which would turn on or open the main 10 valve *B* should it be depressed by means of its chain *II'*, and in the figures it is shown as so depressed or turned on. One of the chains *II'* and the chain *F* (attached to the igniting-valve *D*) are connected together in such a 15 manner that if a pull be exerted upon both chains at the same time by means of the common ring *I'* both main valve *B* and igniting-valve *D* will be opened to their fullest extent.

20 *J* represents an ordinary alcohol or other torch. To the side of its stem is attached a projection or hook *K*, designed to engage in either one of the rings at will.

The operation of the device is as follows: 25 If the parts be in their normal position, the igniting-valve *D* being closed firmly upon its seat by its spring, and the main supply-valve *B* also closed, its arm *G'* being elevated instead of depressed, as shown in the figures, 30 the alcohol torch *J* is first lighted and its projection *K* engaged with the ring *I'*. If now the torch *J* is drawn downward, the ring *I'* will also be pulled downward and the main valve *B* opened to its widest extent by the lever-arm *G'* 35 assuming the position shown in the figure, and at the same instant the igniting-valve *D* will be opened fully. The gas will then pass through the main valve downward first to the burners, filling them and expelling the air, and 40 then through the igniting-valve *D* into the flash-pilot pipe *E*, issuing through the various apertures made therein. That issuing from the lower aperture *k* will be projected downward, as shown by the dotted lines, striking 45 the flame at the top of the torch, which will ignite it, and this ignited jet will consequently ignite that proceeding from the upper opening *j*, which latter jet will ignite those above it, so that the flame will travel upward along 50 the flash-pilot to the extreme end thereof, thereby lighting the burners upon the cluster from a point above the chimneys. If the pull upon the ring *I'* be now relaxed, the igniting-valve will be closed by means of its 55 spiral spring *h*, thereby extinguishing all of the jets in the flash-pilot, but leaving the burners lighted. The burners of the group may be extinguished at any time by pulling the ring *I'* downward.

60 Referring to Fig. 1, the igniting device is shown in connection with a cluster inclosed within a glass globe. In this case, as the main valve *B* is located above the cluster, the turning on of the main gas-jet is independent of 65 the turning on of the igniting-valve. A small opening *L* is left at the base of the globe *M*, through which the chain *F* passes from

the igniting-valve *D*, which is located within the globe, as shown, its ring being attached exteriorly. The operation here consists in 70 first turning on the main valve *B*, as by pulling the proper dependent chain, after which the hook upon the ignited torch is introduced into the ring *I'* and a downward pull exerted, which opens the igniting-valve, causing its 75 downward jet to pass through the opening in the glass globe and become ignited at the lighted end of the torch. As before, when the pull is relaxed, the igniting-valve closes, extinguishing the flash-pilot. 80

In Figs. 4 and 5 the igniting-valve consists of an ordinary stop-cock *N*, about the plug of which is arranged a spring *O*, which tends to keep the said cock *N* normally closed. The operation of ignition as far as the valve 85 and pilot-tube are concerned is the same as that described, as shown in Figs. 1 and 2. In these figures is also shown a modification of the flash-pilot. Instead of the flash-pilot proceeding upward and terminating above the 90 chimneys of the burners it branches at the point *P*, each of the branch arms separately passing within the Welsbach burner to the proper igniting-point. This latter form is in 95 some cases preferable to that first described of lighting from the top, particularly where a gas of heavy specific gravity, like machine or gasoline gas, is employed, the latter having a tendency to fall instead of to rise.

I do not limit myself to the use of any specific kind of valve to control the igniting-supply, as it is to be plainly understood that any of the usual forms of cocks or valves could be used. This is also true regarding the flame or spark making torch, as any instrument will serve to ignite the downward jet that is capable of bringing such jet to igniting temperature. Although preferable, it is not necessary that the valve be pulled open by the torch itself, as the torch could be held 100 in one hand and the igniting-valve opened with the other or by any other means.

I claim—

1. In a gas-lighting apparatus, the combination with burners, of a flash-pilot, a main valve controlling the gas supplied to the burners, a supplemental valve controlling the gas supplied to the flash-pilot, a spring tending to normally close said supplemental valve, an operating-ring *I*, a flexible connection between said operating-ring and the supplemental valve, and a separate flexible connection between said operating-ring and the main valve, whereby the said valves will be opened simultaneously by the operation of 115 said ring but the supplemental valve will be allowed to close without affecting the position of the main valve, substantially as set forth.

2. In a gas-lighting apparatus, the combination with burners, of a flash-pilot having a downwardly-extending opening at its lower part by which the flame from the pilot will 120 be projected downwardly away from the

same, and other openings in said flash-pilot from which gas will flow and will be ignited by said initial flame, a main valve controlling the gas supplied to the burners, a supplemental valve controlling the gas supplied to the flash-pilot, a spring tending to normally close said supplemental valve, an operating-ring I, a flexible connection between said ring and the main valve, a flexible connection between said ring and the supplemental valve, and a torch for engaging said ring, the said ring being so disposed to the downwardly-extending opening that the initial jet may be ignited by the torch in depressing said ring, whereby both valves will be opened simultaneously but the supplemental valve will be allowed to close with-

out affecting the position of the main valve, substantially as set forth.

3. In a gas-igniting apparatus, the combination of burners with an inclosing globe, an aperture in said globe, gas-valves for the burners operating through said aperture, and a flash-pilot wholly within the globe having a hole pierced therein for projecting gas through said aperture, for the purpose substantially as set forth.

This specification signed and witnessed this 28th day of April, 1897.
